[57] **CLAIM**

The ornamental design for a wheeled standing platform for a baby carriage or stroller, as shown and described.

DESCRIPTION

FIG. 1 is a bottom front perspective view of a wheeled standing platform for a baby carriage or stroller showing the front side view, left side view and bottom view of my new design;

FIG. 2 is a bottom plan view thereof;

FIG. 3 is a top perspective view, showing the top view and left side view thereof;

FIG. 4 is a top front perspective view showing the front end view and top view thereof;

FIG. 5 is a rear perspective view showing the rear side view and top view thereof;

FIG. 6 is a top perspective view showing the right side view and top view thereof, with the wheels removed;

FIG. 7 is a bottom front perspective view showing the bottom view and front view thereof, with the wheels removed;

FIG. 8 is a bottom rear perspective view showing the bottom view, right side view and rear view thereof, with the wheels removed; and,

FIG. 9 is a front perspective view showing a front view and right side view thereof, with the wheels removed.

The right side view is a mirror image of the left side view.
